United States Patent Office

Des. 204,821
Patented May 17, 1966

204,821

LITTER BAG

Louis G. Standard, 3042 Earlmar Drive,
Los Angeles, Calif.

Filed Mar. 22, 1965, Ser. No. 84,393

Term of patent 14 years

(Cl. D58—2)

FIG. 1 is a front elevational view of a litter bag, showing my new design;

FIG. 2 is a rear elevational view thereof;

FIG. 3 is an edge view thereof;

FIG. 4 is a top edge view thereof; and

FIG. 5 is a bottom edge view thereof.

I claim:

The ornamental design for a litter bag, substantially as shown.
